UNITED STATES PATENT OFFICE.

PHILIP MUELLER AND ANTON C. SCHUERMANN, OF DECATUR, ILLINOIS, ASSIGNORS
TO ADOLPH MUELLER, TRUSTEE, OF DECATUR, ILLINOIS.

WASTE STOPPER AND OPERATING MECHANISM.

Original application filed November 12, 1919, Serial No. 337,496. Patent No. 1,447,808, dated March 6, 1923. Divided and this application filed April 18, 1922. Serial No. 554,442.

To all whom it may concern:

Be it known that PHILIP MUELLER and ANTON C. SCHUERMANN, citizens of the United States, residing at Decatur, in the county of Macon and State of Illinois, have invented new and useful Improvements in Waste Stoppers and Operating Mechanism, of which the following is a specification.

This invention relates to waste stoppers for bowls, lavatories, and analogous devices, and to an improved construction in the operating mechanism thereof. The present case is a division of application, Serial No. 337,496, filed Nov. 12, 1919, Patent No. 1,447,808, March 6, 1923.

It is customary in waste stopper constructions of this type to have parts of the operating mechanism disposed within the stopper, which necessarily has a tendency to obstruct the passage of water and foreign material passing through the stopper and eventually cause the clogging or stopping up of the waste outlet.

In order to overcome these defects, the present development provides means arranged outside of the stopper, for actuating the same, so as to permit a free and unobstructed passageway through the waste outlet.

The present invention has further for its object an adjustable waste fitting that is adapted for use with bowls of different thickness, and bowls in which the waste outlet is positioned at different heights relative to the faucet or supply spout.

A still further advantage of the present construction resides in providing an actuating mechanism in which the lifting rod is adapted to give a straight lift to the stopper without imparting any turning movement to any of the parts, thus dispensing with the complicated connections employed in similar devices, wherein a rotary movement is imparted to the stopper for effecting operation of the same.

In the drawings herewith illustrating embodiments of our invention,

Figure 1 is a view in central vertical section of a bowl equipped with a waste fixture made in accordance with our invention.

Figure 2 is a horizontal sectional view on substantially the line 2—2 of Figure 1, showing the waste stopper and its actuating yoke,

Figure 3 is a detail view in vertical section on the line 3—3 of Figure 2.

Referring to the drawings, wherein like numerals denote like parts in the various views, 10 designates a wash bowl of any suitable material, design, and dimensions, and preferably composed of vitreous ware, although it is obvious that our invention is adapted to bowls of varied material and construction.

The bowl 10 is formed with the usual bowl slab 11, a back slab 12, and may be provided with an overflow 13 leading to the waste outlet arranged in the bottom of said bowl.

The said waste outlet is provided with a sleeve fitting 14, passing through and below the bottom of the bowl, and formed at its upper end with an outwardly extending shoulder 15, which is adapted to abut the gasket 19 preferably arranged in the recess in the bottom of the bowl 10. The sleeve 14 extends an appreciable distance below the bowl and is externally threaded throughout the greater part of its length so that the adjustable housing 16 and the packing 17 may be effectively secured to the bowl.

A hollow tubular stopper 18 is provided at its upper end with a conical head 18' adapted to abut against and be supported by a conical seat in the end of the sleeve 14. The stopper is further provided at its upper end with a plurality of slots 20 for permitting the passage of water from the bowl to the waste outlet. In order that the waste stopper 18 may be locked in place against accidental removal, it is slotted at 21, said slot being engaged by a screw 22 threaded in the wall of the casing 16. The lower end of the stopper 18 is provided with diametrically opposed grooves 23, and flat sides 24, as shown in Figures 2 and 3, for a purpose now to be set forth.

An actuating yoke 25 is adjustably mounted on a lifting rod 26 passing through the housing 16. The arms 27 of said yoke are normally arranged to straddle the lower end of the waste stopper and fit within the grooves 23, thus preventing the disengagement or removal of the stopper from the arms 27 until the flattened portions 24 are arranged in parallel alignment therewith, whereupon the waste stopper may be readily

withdrawn. The lifting rod 26 passes through a stuffing box 27 formed in an offset portion of the casing 16, and its movement is steadied by means of a guiding lug 28 formed in the interior of the housing and through which the lower end of the said rod is adapted to pass.

A substantially L-shaped member 29 is adjustably connected to the rod 26 by the pin 30, which is threadedly connected to the member 29. An operating rod 31 is similarly secured to the vertical portion of the member 29, and passes through and beyond the supply spout 32 so as to provide at its upper end an operating knob or handle 33 for actuating the waste stopper 18. A tube 34 surrounds the operating rod within the supply spout and is threaded or otherwise secured at its upper extremity within the neck of the spout 32, and at its lower end to the securing nut 35.

With this arrangement it will be seen that a suitable range of adjustment is provided to meet different conditions arising through the variations of the thickness of the bowls 10, or the positioning of the supply spout 32 at different angles with respect to the waste stopper 18. Furthermore, by arranging the arms 27 of the fork 25 to exteriorly embrace the stopper 18, an unobstructed passage is provided within the stopper so that water and foreign material may easily and freely pass therethrough without danger of obstructing sediment and clogging up the outlet.

By reason of the ready removal of the stopper 18 from the housing 16 and the fork 25, the parts may be expeditiously and economically renewed, while by avoiding any turning movements of the stopper, and permitting the operation thereof to be accomplished by a straight lift applied to the lifting rod 31, the stopper mechanism is reduced to a minimum number of parts without in any way detracting or lessening its efficiency.

It is to be understood, that the form of the invention herewith shown and described, while a preferred embodiment of the same is merely illustrative and in no sense restrictive, for the construction may be varied as to mechanical details without departing from the spirit of the invention and the scope of what is claimed.

We claim:

1. The combination in a fitting of the class described, of a stopper, a stopper casing into which the lower end of said stopper projects, a vertically disposed lifting rod extending from said casing, a vertically adjustable yoke on said rod and embracing said stopper, and means on said stopper for locking the parts together when the stopper is rotated in a predetermined position.

2. The combination in a fitting of the class described, of a stopper, a stopper cas-

ing into which the lower end of said stopper projects, a vertically disposed lifting rod extending from said casing, a vertically adjustable yoke on said rod and embracing said stopper, means on said stopper for locking the parts together when the stopper is rotated in a predetermined position, and means in said casing for guiding the lower end of said lifting rod.

3. The combination in a fitting of the class described, of a stopper having a grooved lower end and flattened opposite sides, a stopper casing into which the lower end of said stopper projects, a lifter rod in said casing projecting exteriorly thereof, a yoke adjustably mounted on said lifter rod and engaging said grooved stopper, and means to prevent accidental rotation of said stopper and disengagement of said yoke, said means being removable to permit the stopper to be rotated in the yoke and withdrawn when the flattened sides are brought to a predetermined position.

4. The combination in a fitting of the class described, of an operating yoke, and a stopper having a grooved lower end and flattened opposite sides to permit it to be engaged with or disengaged from said yoke.

5. The combination of a waste stopper, a stopper lifting yoke straddling said stopper, and in rotatable relation thereto, and means on the periphery of said stopper to lock the stopper and yoke for simultaneous reciprocating movement when rotated to a predetermined angular relation and to permit their independent movement and separation when rotated to another angular relation.

6. The combination of a waste stopper having an interrupted groove in its outer wall, and a yoke straddling said stopper and engaging said groove to lock the parts together for simultaneous reciprocation in a predetermined angular relation, said stopper and yoke being independently movable and separable when the yoke is brought into register with the interruptions in the groove.

7. The combination in a fitting of the class described, of a waste stopper casing having an enlarged chamber, a waste stopper in said casing having an interrupted groove formed in its outer wall, stopper lifting means in said chamber engaging said interrupted groove, and means extending vertically outside of said casing to move said operating means and said stopper.

8. The combination in a fitting of the class described, of a waste stopper casing having a laterally offset chamber, a waste stopper in said casing with its lower end adjacent said chamber provided with an interrupted groove, a stopper lifting yoke engaging said groove and projecting laterally into said chamber, and a vertical lifter rod mounted in guides in and projecting

- outside of said chamber to engage and lift said yoke and stopper.
9. The combination in a fitting of the class described, of a waste stopper casing having a laterally offset chamber, a guide within said chamber, a waste stopper in said casing with its lower end adjacent said chamber, a vertically disposed lifting rod projecting into said chamber and through said guide, and a stopper lifting yoke connecting said lifter rod and stopper, said yoke being adjustable vertically on said rod.
10. The combination in a fitting of the class described, of a waste stopper casing having a straight passage therethrough to

receive a waste stopper and an interrupted groove in its outer wall a laterally offset chamber in said passage below the bowl, a stuffing box in the upper wall of said chamber, a waste stopper in said casing with its lower end adjacent said chamber, a vertically disposed lifter rod mounted in said chamber with its end projecting through said stuffing box, means integral with said chamber for guiding said lifting rod, and a stopper lifting yoke, adjustably mounted on said rod embracing said groove.

In testimony whereof we have hereunto set our hands.

PHILIP MUELLER.

ANTON C. SCHUERMANN.
